UNITED STATES PATENT OFFICE.

JOHN A. STARR, OF MAYVILLE, WISCONSIN.

MAIL-BAG MECHANISM.

1,424,858.

Specification of Letters Patent. Patented Aug. 8, 1922.

Application filed November 13, 1920. Serial No. 423,958.

To all whom it may concern:

Be it known that I, JOHN A. STARR, a citizen of the United States, residing at Mayville, in the county of Dodge and State 5 of Wisconsin, have invented certain new and useful Improvements in Mail-Bag Mechanisms, of which the following is a specification, reference being had to the accompanying drawings.

10 This invention relates to certain improvements in mail bag mechanisms and has relation more particularly to a combined receiver and support adapted to be positioned adjacent a trackway in such manner where- 15 by mail sacks may be received from and supported for delivery to a passing train, and it is an object of the invention to provide a novel and improved device of this general character which embodies two vertically spaced and horizontally swinging arms 20 or cranes which automatically swing from a working position with respect to the trackway into an inoperative position as a result of the impacts created during a transfer 25 of the bags to and from a passing train, whereby movements of the arms or cranes effectively take up or absorb the force of the impacts.

It is also an object of the invention to pro- 30 vide a device of this general character including a swinging or movable crane or arm provided with a receiving cross-head, together with automatically operating means for holding the bag against displacement 35 after being caught or received by the cross-head.

An additional object of the invention is to provide a device of this general character embodying a swinging or movable arm or 40 crane provided with novel and improved means for holding a mail bag in a manner whereby the same may be effectively and conveniently transferred to a passing train.

The invention consists in the details of 45 construction and in the combination and arrangement of the several parts of my improved mail bag mechanism whereby certain important advantages are attained and the device rendered simpler, less expensive 50 and otherwise more convenient and advantageous for use, as will be hereinafter more fully set forth.

The novel features of my invention will hereinafter be definitely claimed.

55 In order that my invention may be the bet-

ter understood, I will now proceed to describe the same with reference to the accompanying drawings, wherein:

Figure 1 is a view in side elevation of a mail bag mechanism constructed in accordance with an embodiment of my invention, the receiving and supporting crane being shown in working position.

Figure 2 is a view in top plan of the supporting arm or crane as herein embodied.

Figure 3 is a fragmentary view in top plan showing the supporting crane or arm in a second or inoperative position.

Figure 4 is a fragmentary sectional view taken substantially on the line 4-4 of Figure 1, looking in the direction of the arrow.

Figure 5 is an enlarged fragmentary sectional view taken longitudinally of the outer or free end portion of the supporting arm or crane with certain of the parts in elevation.

Figure 6 is a detail sectional view taken substantially on the line 6-6 of Figure 5.

Figure 7 is a fragmentary view in perspective of the lower or forked end of the arm depending from the brace member.

Figure 8 is a view in top plan of the receiving arm as herein embodied, certain of the parts being in section and said arm being shown in working or operative position.

Figure 9 is a view similar to Figure 8 with the upper member of the arm or crane broken away.

Figure 10 is an enlarged longitudinal sectional view taken through the outer or working end portion of the receiving arm or crane.

Figure 11 is a view partly in section and partly in elevation illustrating the means for automatically swinging the receiving crane or arm into inoperative position.

Figure 12 is an enlarged fragmentary view partly in section and partly in elevation illustrating in detail the gripping member as herein disclosed.

Figure 13 is a fragmentary view partly in section and partly in elevation illustrating in detail one of the pulleys carried by the receiving arm or crane and illustrating the manner whereby the flexible member is attached thereto.

Figure 14 is a view in perspective of the arm with which the gripping member is operatively engaged, and

Figure 15 is a fragmentary view partly in

elevation and partly in section illustrating a pair of catches as herein embodied for action with the receiving arm or crane.

As disclosed in the accompanying drawings, 1 denotes a vertically disposed post or standard positioned to one side of a trackway and arranged at opposite sides of said post or standard at preferred distances therefrom and alined therewith in a direction substantially at right angles to the trackway, are the supplemental posts or standards 2 of a height materially less than the height of the post or standard 1.

Keyed or otherwise fixed to the upper portion of the post or standard 1 at a point slightly below the upper end of said post is a sleeve 3 having a forwardly extending wing or lug 4 having its upper face flat and flush with the upper end of the sleeve 3. The forward end of the wing or lug 4 at the transverse center thereof has disposed thereacross the groove or recess 5 and the portions of said forward edge at opposite sides of said groove or recess 5 are inclined outwardly and rearwardly therefrom, as at a, to provide cam faces for a purpose to be hereinafter more particularly referred to.

C denotes a supporting crane or arm of required length and which is preferably flattened and coplanar from end to end. Adjacent its rear end portion, the crane or arm C is laterally enlarged to provide a substantially circular bearing 6 provided at its axial center with the opening 7 through which the upper portion of the post or standard 1 extends with said bearing 6 resting upon the upper end of the sleeve 3 and the corresponding face of the wing or lug 4.

The portion of the post or standard 1 above the crane or arm C is bifurcated; and extending through the kerf 8 provided by such bifurcation is a plate 9 extending beyond opposite sides of the post or standard 1 and keyed or otherwise held, as at 10, in applied position. The extended portions of the plate 9 radiate from the post or standard 1 on angles of substantially 45° with respect to the plane of the posts or standards 1 and 2.

50 The portion of the crane or arm C rearwardly of the bearing 6 has superimposed thereon a plate 11 provided at its inner end with the transversely spaced upstanding wings or lugs 12 adapted to contact with the extended portions of the plate 9, the relative position of said wings or lugs 12 with respect to the transverse center of the crane or arm C being such that the contact of said wings or lugs 12 with the extended portions 55 of the plate 9 limits the swinging movement of the crane or arm C within an arc of substantially 90°, with said crane or arm C, when in one position, substantially coplanar in a vertical direction with the alined posts or standards 1 and 2.

The outer end portion of the plate 11 is held to the adjacent end portion of the crane or arm C by the bolt 14 or the like while the marginal portions of said plate 11 adjacent the opposite end thereof are provided with the depending lugs 15 overlying the edges of the crane or arm C.

B denotes a brace member having one end portion anchored by the bolt 16 or the like to substantially the central portion of the arm 75 or crane C in advance of the post or standard 1. The brace B has a downwardly and rearwardly inclined portion 17 terminating in the horizontally disposed extension 18. The extension 18 at a point in close proximity to the lower part of the inclined portion 17 is provided with an opening 19 through which the post or standard 1 is directed while the outer end portion of said extension 19 has bolted or otherwise secured thereto, as at 20, the lower end portion of a vertically disposed brace 21. The upper end portion of this brace 21 is anchored to the adjacent end portion of the crane or arm C by the bolt 14, hereinbefore referred to, or otherwise as may be preferred.

Encircling the post or standard 1 above the extension 18 of the brace B is a coil spring 22 having its upper end portion anchored to the post or standard 1 and its opposite end portion anchored to the brace 21, whereby the spring 22 operates to constantly urge the crane or arm C toward the limit of its movement substantially at right angles to the plane of the alined posts or standards 1 and 2.

23 denotes an upstanding flat arm carried by the forward end portion of the crane or arm C and provided at its lower end with a foot 24 resting upon said end portion of the crane or arm C, and provided with the lugs 25 overlying the adjacent edges of the crane or arm C. The portion of the arm 23 immediately adjacent the foot 24 is provided with a relatively broad and longitudinally directed slot 26.

The upper portion of the arm 23 is provided with forwardly directed and transversely spaced lugs 27 which overlap inwardly directed and transversely spaced lugs 28 carried by the upper portion of a vertically directed arm 29. The upper portions of the arms 23 and 29 are hingedly connected for relative swinging movement in a direction longitudinally of the crane or arm 120 C by the pin 30 directed through said overlapping lugs 27 and 28.

The connected end portions of the arms 23 and 29 are provided with the upwardly and inwardly directed arcuate arms 31, the free or opposed end portions of which are adapted to abut to limit the outward swinging movement of the arm 29 with respect to the arm 23. The inward swinging movement of the arm 29 with respect to the arm 130

23 is limited by the transversely disposed fingers 32 carried by the arm 29 substantially midway of its length, the free end portions of said fingers 32 contacting with the 5 arm 23. The arms 23 and 29 are also held against relative lateral swinging movement, and particularly when strain is imposed upon the arm 29, by a pin 33 freely directed through the central portions of the arms 23 10 and 29.

Slidably disposed through and supported by the lower portion of the arm 29 but at a point above the upper face of the arm or crane C is an end portion of an elongated 15 rod 34 extending inwardly and longitudinally of the arm or crane C. Said rod 34 outwardly of the arm 29 is provided with an enlargement or head 35 with which the arm 23 contacts when swung or moved outwardly and whereby outward endwise movement is imparted to the rod 34.

The rod 34 is freely disposed through a guiding loop or eye 36 comprised in the head of the bolt 16. The inner end portion 25 of the rod 34 is downwardly offset, as at 37, said offset portion being freely disposed through a longitudinally directed slot 38 provided in the inner end portion of the crane or arm C. The inner end portion of 30 the rod 34 below the crane or arm C is freely directed through a depending guide eye or sleeve 39 carried by the crane or arm C. The inner end portion or extremity of 35 the rod 34 is adapted to engage within the groove or recess 5 to hold the arm or crane C in working position or in a position whereby the same is substantially coplanar in a vertical direction with the alined posts or standards 1 and 2.

40 The rod 34 is adapted to be urged inwardly by a coil spring 40 encircling the forward end portion of the rod 34 and interposed between the arm 29 and an enlargement 41 carried by the rod 34 at a 45 point in relatively close proximity to the head 35. The slot 26 in the arm 23 is of such dimensions to readily permit the enlargement 41 to have unobstructed passage therethrough. As herein disclosed, the enlargement 41 constitutes a nut threaded upon the adjacent end portion of the rod 34 so that said enlargement or nut may be 50 adjusted lengthwise of the rod 34 to regulate or vary the tension of the spring 40 to best comply with the requirements of practice.

The lower end portion of the arm 29 is continued by a forwardly directed extension 42 terminating in a block or head 43. 55 The forward or outer end portion of the block 43 is provided with a socket 44 in which is rotatably received a shank 45. The shank 45 is provided with an upstanding pin 46 disposed through a transversely directed slot 47 provided in the upper por-

tion of the block or head 43. The outer end portion of the shank 45 is provided with a head 48, herein disclosed as circular in form, and extending outwardly and forwardly from the lower portion of said head 48 are the transversely spaced fingers 49. The outer end portions of the fingers 49 are tied or connected by the cross member 50 with which is adapted to be engaged the hook 51 extending outwardly from a ring 52 comprised in a mail bag holder H. The opposed faces of the fingers 49 in advance of the member 50 are outwardly beveled, as at 53, to facilitate the requisite engagement of the hook 51 with said cross member. 80

54 denotes an arcuate arm depending from the crane or arm C at a point inwardly of its outer end, and the upper portion of said arm 54 is provided with an extension 55 underlying said crane or arm C and anchored thereto by the bolt 16, hereinbefore referred to. The side marginal portions of the extension 55 are provided with the upstanding flanges 56 extending over the adjacent edges of the crane or arm C whereby said arm 54 is held against turning movement about the bolt 16 and thereby maintained in desired position. The curvature of the arm 54 is downwardly and forwardly and the lower end portion of said arm is 95 provided with a longitudinally disposed slot 57 open at the lower end of said arm.

Insertable within the slot 57 is a flanged sleeve or collar 58 through which is freely directed the gripping member G. The member G comprises a single strand of resilient material bent centrally upon itself to provide an eye or loop 59 and the elongated arms 60, said arms 60 terminating in the inwardly facing jaws 61. The loop 59 and 100 jaws 61 limit the movement of the gripping member G through the sleeve or collar 58 and also serve to hold said gripping member and collar or sleeve normally against complete separation. The natural tendency 105 of the arms 60 is to separate so that when the member G is moved inwardly through the sleeve or collar 58, the jaws 61 will effectively engage the second ring 62 comprised in the holding member H. 110

Suitably secured to the loop 59 of the gripping member G is an end portion of a retractile member or coil spring 63, the opposite end portion of said member or spring 63 having secured thereto an end portion of 115 a flexible member 64 herein disclosed as a chain.

Suitably secured to the forward or under face of the brace B at a point preferably above the lower end portion of the arm 54 is a bracket 55 which rotatably supports a guide pulley 66 over which passes the flexible member or chain 64. The bracket 55 has extending forwardly and downwardly therefrom and below the pulley 66 an elongated 120

arm 67 coplanar in a vertical direction with the crane or arm C. The lower or forward end portion of the arm 67 is provided with a fork 68 adapted to have locking engagement with the flexible member or chain 64 to normally hold the gripping member G against outward movement when the jaws 61 thereof have gripping action upon the ring 62. The free end portion of the flexible member or chain 64 is provided with a ring 69 or the like to facilitate the desired pull being imposed upon said member or chain 64 and the free end portion of the member or chain 64 is normally suspended by engagement of said ring 69 with a hook 70 extending laterally and upwardly from the brace member B.

The holding member H, hereinbefore referred to, comprises the rings 52 and 62, hereinbefore referred to, and which are tied or connected by the flexible member or strap 71. The mail bag M has secured thereto at longitudinally spaced points the inwardly facing hook members 72 with which the rings 52 and 62 are engaged and each of said hook members 72 is provided with a holding or locking tongue 73 whereby the hook members 72 are held against accidental disengagement from their coating rings 52 and 62.

Normally, the crane or arm C is in a position extending in the same general direction as the trackway and when a bag is to be engaged therewith for transfer to a passing train, the large ring 52 has its hook 61 engaged with the cross member 50. The flexible member or chain 64 is disengaged from locking engagement with the fork 68 so that the gripping member G, or more particularly the jaws 61 thereof, may be properly engaged with the second hook member 62 and which engagement is maintained by imposing pull or strain upon the flexible member or chain 64. As the gripping member G is pulled inwardly, the arms 60 swing one toward the other, resulting in an effective clamping action of the jaws 61 upon the ring 62. When the desired engagement of the jaws 61 with the ring 62 has been effected, the flexible member or chain 64 is interlocked with the fork 68, whereby said engagement is maintained. As the train passes with the receiving hook R thereof properly extended, the same passes through and grasps the ring 52 and on account of the yielding movement permitted by the retractile member or spring 63, the gripping member G will move forward sufficient to permit the desired separating movement of the jaws 61 with the consequent release of the ring 62. The receiving hook R also results in a release of the hook 51 from the cross member 50.

To facilitate the release or disengagement 65 of the hook 51 from the cross member 50,

the shank 45 partially rotates. However, normally the forwardly directed fingers 49 carried by the head 48 of the shank are aligned horizontally and are maintained in such position by the extensions 74 of a coil 70 spring 75 engaging the opposite sides of the upstanding pin 46. The coil spring 75 encircles an upstanding arm 76 carried by the rear portion of the head or block 43. The coil spring 75 is held on the arm 76 by the 75 nut 77 threaded on the arm above the spring.

The head or block 43 is also provided with an upstanding lug or finger 78 at a position adjacent a side edge of the slot 47 and at the center thereof and which operates to 80 limit the inward movement of the extensions 74 of the spring 75 and whereby it is assured that the pin 46 will be normally maintained in a vertical position, and the fingers 49 normally maintained spaced apart in a horizontal direction, as hereinbefore referred to.

After a bag to be transferred to a passing train has been properly applied to the crane or arm C, said crane or arm is swung around into a position vertically coplanar with the 90 aligned posts or standards 1 and 2. The weight of the applied mail bag M results in a slight inward swinging movement of the arms 29 which place the spring 40 under sufficient tension to force the rod 34 inwardly 95 and as the crane or arm C is swung or moved around into operative or working position, the inner end portion of the rod 34 will ride over a cam face α and automatically seat within the groove or recess 5 whereby the 100 arm or crane C is positively held in its working or operative position.

After the applied mail bag M has been transferred to the receiving hook R of the passing train, the resultant expansion of 105 the spring 40 will cause the arm 29 to swing outwardly and during which movement the arm 29 will contact with the enlargement 35 at the adjacent end of the rod 34 and move said rod 34 sufficiently to release the same 110 from within the groove or recess 5, whereupon the crane or arm C under the influence of the coil spring 22 will be automatically returned to its normal inoperative position or in a position extending in the same general direction as the trackway.

A denotes a receiving arm or crane provided at its outer end with a cross member or head 79 extending at substantially equal distances beyond the opposite sides of the arm or crane A. The arm or crane A from the cross member or head 79 to its opposite end embodies vertically spaced members 80 having their forward portions converging toward the cross member or head 79 with the rear portions thereof substantially in parallelism.

The parallel portions of the members 80 substantially midway thereof are enlarged transversely, and at substantially the center 130

of each of said enlarged portions 81 is an opening 82 defined by an outstanding bearing sleeve or collar 83 and through which the post or standard 1 is directed; and 5 whereby the arm or crane A is capable of swinging movement in a horizontal path at a desired point below the upper or supporting crane or arm C. The free end portions of the parallel portions of the members 80 10 of the arm or crane A are tied or connected by the bolt 84, and surrounding said bolt 84 and interposed between said extremities of the horizontal portions of the members 80 is the spacing sleeve 85.

15 Fixed to the post or standard 1 between the parallel portions of the members 80 of the arm or crane A is a sleeve or collar 86 arranged at the central portion of a horizontally disposed substantially circular plate 87 and which plate, at diametrically opposed points and in a direction longitudinally of the aligned posts or standards 1 and 2, is provided with the recesses 88 and 89, the rear recess 88 being relatively broad and the 20 forward recess 89 restricted. The outer side marginal portions of the recesses 88 and 89 are rounded to merge with the peripheral edge of the plate 87 for a purpose which will hereinafter be clearly understood.

25 30 Rotatably supported by the forward end portion of the arm or crane A and in relatively close proximity to the cross member or head 79 is a vertically disposed shaft 90 provided at its upper portion and above the top member 80 with a substantially circular enlargement or head 91 provided in its periphery with the circumferentially spaced notches or recesses 92, said notches or recesses being two in number and spaced apart 35 about 135° .

40 Fixed to the shaft 90 is a pulley 93 provided with the oppositely directed arcuate arms 94 having their inbow edges disposed generally in a direction toward the cross member or head 79. Each of said arms 94 is of a length to contact with an outer end portion of the member or head 79 when a notch or recess 92 is positioned at substantially the transverse center of the upper member 80 of the arm or crane A.

45 55 At the transverse center of the upper member 80 of the arm or crane A inwardly of the enlargement or head 91 and immediately adjacent thereto is an upstanding guide loop or eye 95 through which is slidably directed an end portion of a locking bolt 96. The opposite or rear end portion of the bolt 96 is slidably disposed through a block 97 provided at its opposite sides with 60 the outstanding trunnions 98 rotatably engaged with and supported by the flanges 99 depending from the rear marginal portion of an elongated arm 100. Interposed between the block 97 and the outstanding abutment 101 carried by the forward end por-

tion of the bolt 96 is an expansible member 102 herein disclosed as a coil spring encircling said bolt and which operates to force said bolt 96 outwardly or in a direction toward the enlargement or head 91. The 70 inner or rear end portion of the elongated arm 100 is provided with a depending rigid strip or extension 103 freely passing through a longitudinally directed slot 104 in the upper member 80 of the arm or crane A and 75 having its lower end portion pivotally engaged with a cross member 105 intersecting the longitudinally directed slot 106 provided in the lower member 80 of the arm or crane A. By this means, the arm or member 100 is supported for vertical swinging movement and the upper vertical movement of said member or arm 100 is automatically effected by the retractile member or coil spring 107 having one end portion secured to the depending strip or extension 103 at a desired point above its pivotal connection with the lower member 80.

80 85 The arm or member 100 is of a length to overlie the enlargement or head 91 and to 90 extend in advance thereof and the forward or free end portion b is adapted to have contact with the upper face of the top member 80 forwardly of the enlargement or head 91. Said extended portion b is provided with a 95 longitudinally directed slot 108 through which is adapted to extend the upstanding staple 109 carried by the top member 80 and through which staple 109 above the portion b of the member or arm 100 is adapted to be 100 inserted a lock 110 or other locking means for maintaining the member or arm 100 at the limit of its downward movement.

105 110 When the member or arm 100 is in its downward position, the forward end of the locking or sliding bolt 96 is constantly urged by the expansible member or spring 102 toward the head or enlargement 91, whereby said bolt will contact with the periphery of said head or enlargement between the recesses or notches 92 and automatically extend into either of said recesses or notches when the shaft 90 has been rotated to bring said notch or recess 92 into substantially longitudinal alignment with the bolt 96. A 115 notch or recess 92 is brought into this particular position when the shaft 90 has been sufficiently rotated to bring the outer end portion of an arm 94 substantially into contact with an outer end or extremity of the 120 cross head or member 79.

125 130 Connecting the inner extremities of the parallel portions of the members 80 of the arm or crane A is a vertically disposed journal rod or stationary shaft 111 surrounded by a hub or sleeve 112 capable of free rotary movement. The lower portion of the hub or sleeve 112 carries a pulley 113 preferably of a diameter materially greater than the diameter of the pulley 93 hereinbefore re-

ferred to. A portion of the groove of the pulley 113 is recessed, as at 114, and intersecting the central portion of said recess in close proximity to the periphery of the 5 pulley 113 is a pin 115 of a length to extend a desired distance above the pulley 113. The inner end portion of the retractile member or spring 102, hereinbefore referred to, is secured to the extended portion of this pin 10 115 whereby the member or spring 102 in addition to automatically moving the elongated member or arm 100 upwardly serves to normally maintain the pin 115 at substantially the transverse center of the members 15 80 of the arm or crane A and in advance of the rod or shaft 111.

Wrapped around the forward pulley 93 is a flexible member or wire 116. The opposite end portions of the member or wire 20 116 extend rearwardly of the arm or crane A and are secured to the forward end portions of the coil springs 117. The opposite or inner end portions of the springs 117 are secured to end portions of a flexible member 25 or wire 118 which is disposed around the inner pulley 113 and within the recess 114 in the groove of the pulley 113 and inwardly of the pin 115 whereby said flexible member or wire 118 is held against slipping 30 movement around the pulley 113 and whereby the springs 117 will be maintained at a substantially equal tension.

The hub or sleeve 112 diametrically to the pin 115 has radiating therefrom an arm or 35 lug 119 having its outer or free end rounded and of a length greater than the distance between the hub or sleeve 112 and the major curved or arcuate edges of the plate 87, so that when the arm or crane A is vertically 40 coplanar at either side of the alined posts or standards 1 and 2, the outer or free end portion of the arm or lug 119 will extend within one of the recesses 88 or 89, hereinbefore referred to.

45 Normally, or when the receiving arm or crane A is in an inoperative position, it is disposed away from the trackway in a direction substantially at right angles thereto. When in this position, the arm or lug 119 is 50 arranged within the rear recess 88 in the plate 87. When the lug or arm 119 is in either of the recesses 88 or 89, the arcuate arms 94 are disposed at opposite sides of the arm or crane A in a general direction 55 substantially at right angles thereto. However, during swinging movement of the arm or crane A, the lug or arm 119, when the same passes out of the recess to engage the periphery of the plate 86, will rock the hub 60 or sleeve 112 and through the instrumentality of the pulleys 93 and 113 and the operative connection therebetween as afforded by the flexible members or wires 116 and 118 will rock the arms 94 toward and from the 65 extremities of the cross head or member 79

dependent upon the direction in which the crane or arm A is swung about the post or standard 1. When the arm or crane A is in its operative or working position, these arms 94 are in the general transverse open 70 position hereinbefore referred to and it is preferred that the elongated member or arm 100 be locked in its lowered position after the arm or crane A has been swung into its working or operative position. 75

As a train passes, the bag to be transferred from the train to the arm or crane A is supported thereby in a position whereby the larger ring 52 will be received upon an end portion of the head or member 79 and 80 the force of the impact during this transfer will swing or move the crane or arm A about the post or standard 1 and as the lug or arm 119 swings out of the forward recess 89, the arms 94 will be swung or rocked as hereinbefore described with the free end portion of one of said arms substantially contacting with the extremity of the portion of the cross head or member 79 upon which the ring of the bag is engaged, whereby said bag is held against displacement. The extent of movement of the arms 94 will bring a notch or recess 92 in alinement with the locking or sliding bolt 96 whereupon said bolt will enter into such recess and positively hold the arms 94 against return 85 swinging movement until after the arm or member 100 has been released by the station master or other authorized person, so that 90 the bag caught by the arm or member A is effectively held against displacement from the cross head or member 79 and also against unauthorized removal. However, when preferred, the arm or member 100 can 95 be retained in its raised position so that 100 when the arm or crane A returns to its normal or inoperative position, the arms 94 upon the inward swinging movement of the arm or lug 119 within the rear recess 88 will 105 return to their normal transverse position, 110 as before stated.

The arm or crane A is maintained either in its inoperative position or its operative or working position by the catches 120 carried by the upper end portions of the posts or standards 2. The catches 120 carried by each post or standard 2 are arranged in pairs and oppositely directed and are pivotally supported by the coacting posts or standards 2. The catches 120 are provided 115 with the depending handle members 121 connected by the spring 122 whereby said catches are yieldably held in working position but readily movable to permit the passage of the arm or crane A, or more particularly the lower member 80 thereof, therebetween to be held thereby against swinging movement. 125

Depending from the lower member 80 of the arm or crane A between the post or 130

- standard 1 and the journal rod or shaft 111 and preferably in close proximity to the post or standard 1 is a rod or finger 123 which is adapted to seat within the recess or notch 124 provided in the free end of the inwardly directed arm 125 carried by the hoop 126. The hoop 126 surrounds the post or standard 1 and at a point diametrically opposed to the arm 125 has secured thereto an end 10 portion of a retractile member or coil spring 127, the opposite end portion of said member or spring being anchored to a shank 128 slidably disposed through the upper end portion of the rear post or standard 2. Threaded upon the shank 128 and coacting 15 with said post or standard 2 is a nut 129 which, upon requisite rotation, operates to regulate the tension of the member or spring 127 as the occasions of practice may 20 necessitate.

The member or spring 127 operates to draw or swing the arm or crane A, when moved out of engagement with the catches 120 of the forward post or standard 2 under 25 the influence of the impact or blow incident to the transfer of the mail bag from the passing car to the arm or crane A, to its inoperative position or in a position held between the catches 120 carried by the rear post or 30 standard 2. When the crane or arm A is in this last named position, the post or standard 1 will seat within one of the pockets 130 arranged at opposite sides of the arm 125 adjacent its inner end and whereby the hoop 35 126 is held in such position to assure the proper seating of the depending rod or finger 123 within the notch or recess 124 of the arm 125 when the arm or crane A is swung outwardly into its working or operative position.

In swinging the arm or crane A into its operative position, care must be exercised to have the same move in the required direction in order to assure the proper engagement 45 between the depending rod or finger 123 and the arm 125.

From the foregoing description it is thought to be obvious that a mail bag mechanism constructed in accordance with my invention is particularly well adapted for use by reason of the convenience and facility with which it may be assembled and operated, and it will also be obvious that my invention is susceptible of some change and 50 modification without departing from the principles and spirit thereof and for this reason I do not wish to be understood as limiting myself to the precise arrangement and formation of the several parts herein 55 shown in carrying out my invention in practice except as hereinafter claimed.

I claim:

1. A mail handling mechanism including a station device comprising a standard, 60 a supporting frame rotatably mounted upon

the standard, means under control of an applied mail bag for locking the crane in working position and automatically releasing the same when the mail bag is taken therefrom, automatic means for swinging the crane into 70 a second position when the locking means is released, and a bag supporting means carried by the crane.

2. A mail handling mechanism including a station device comprising a standard, a 75 supporting crane rotatably mounted upon the standard, means under control of an applied mail bag for locking the crane in working position and automatically releasing the same when the mail bag is taken therefrom, 80 automatic means for swinging the crane into a second position when the locking means is released, a bag supporting means carried by the crane, and coacting means carried by the standard and the crane for limiting the 85 movement of the crane in opposite directions.

3. A mail handling device comprising, in combination, a supporting crane provided with engaging means spaced longitudinally 90 thereof, a mail bag, and rings loosely engaged with the side of the bag at points spaced longitudinally thereof and with which coact the spaced engaging means of the crane.

4. A mail handling device including a supporting crane, a member carried by the outer end portion of the crane and supported for rocking movement about an axis extending substantially longitudinally of the crane, 100 said member being provided with outstanding fingers normally spaced apart in a direction transversely of the crane, a cross member connecting said fingers intermediate their ends, and yieldable means coacting 105 with said rocking member for maintaining the fingers of the rotatable member in their normal position.

5. A mail handling device comprising a standard, a crane rotatably supported thereby, an angularly related arm carried by the crane, a second arm pivotally engaged with the first named arm and having swinging movement in a direction longitudinally of the crane, bag engaging means carried by 110 said second arm, and an endwise movable rod carried by the crane and coacting with the standard when the crane is in one position to hold said crane against swinging movement about the standard, said rod and 115 second named arm having coacting means whereby the rod is moved endwise under control of said second arm.

6. A mail handling device comprising a standard, a crane rotatably supported thereby, an angularly related arm carried by the crane, a second arm pivotally engaged with the first named arm and having swinging movement in a direction longitudinally of the crane, bag engaging means carried by 120 125 130

said second arm, an endwise movable rod carried by the crane and coacting with the standard when the crane is in one position to hold said crane against swinging movement 5 about the standard, said rod being loosely directed through the arm and having an enlargement adapted for contact with the outer face of the second arm, and an expansible member coacting with the second named arm 10 and the rod at a point inwardly of said second named arm.

7. A mail handling device including a crane and bag supporting means carried by the crane at points spaced longitudinally 15 thereof, one of said means including an arm depending from the crane, a gripping member slidably supported by the arm, and retractile means for normally holding the gripping member against movement in one 20 direction.

8. A mail handling device including a crane and bag supporting means carried by the crane at points spaced longitudinally thereof, one of said means including an arm 25 depending from the crane, and provided with an open slot, a collar adapted to be slidably engaged within the slot, and a gripping member slidable through the collar and comprising resilient arms normally in convergence and provided with gripping jaws, 30 the movement of the gripping member in one direction through the collar forcing the arms one toward the other, and yieldable means coacting with the gripping member 35 for normally holding the same against movement in the opposite direction.

9. A mail handling device including a crane and bag supporting means carried by the crane at points spaced longitudinally 40 thereof, one of said means including an arm depending from the crane and provided with an open slot, a collar adapted to be slidably engaged within the slot, a gripping member slidable through the collar and 45 comprising resilient arms normally in convergence and provided with gripping jaws, the movement of the gripping member in one direction through the collar forcing the arms one toward the other, a retractile member 50 operatively engaged with the converging end portions of the arms of the gripping member, a flexible member engaged with the retractile member, a guide member carried by the crane and with which the flexible 55 member engages, and means carried by the crane with which the flexible member is adapted to be engaged whereby the gripping member is normally held against movement through the collar in one direction.

60 10. A mail handling device including a crane and bag supporting means carried by the crane at points spaced longitudinally thereof, one of said means including an arm 65 depending from the crane and provided with an open slot, a collar adapted to be

slidably engaged within the slot, a gripping member slidable through the collar and comprising resilient arms normally in convergence and provided with gripping jaws, the movement of the gripping member in 70 one direction through the collar forcing the arms one toward the other, a retractile member operatively engaged with the converging end portions of the arms of the gripping member, a flexible member engaged with the retractile member, a guide member carried by the crane and with which the flexible member engages, and an arm depending from the crane and provided with means to grip the flexible member to normally hold 75 the gripping member against movement in one direction through the collar.

11. A mail handling device comprising a crane provided with a bag engaging means, 80 said means comprising an upstanding arm 85 carried by the crane adjacent its outer end, a second arm positioned in advance of the first named arm, the upper end portions of said arms being pivotally connected, a body carried by the second named arm adjacent 90 the lower end thereof and in advance of said second named arm, a shank rotatably supported by the body, transversely spaced outstanding fingers carried by the shank, a cross member connecting said fingers intermediate their ends, an outstanding pin carried by the shank, said body being provided with a slot through which the pin is directed, and yieldable means contacting with the opposite sides of the pin to normally 95 maintain the fingers of the shank in substantially a horizontal position.

12. A mail handling device comprising a crane provided with a bag engaging means, 100 said means comprising an upstanding arm 105 carried by the crane adjacent its outer end, a second arm positioned in advance of the first named arm, the upper end portions of said arms being pivotally connected, a body carried by the second named arm adjacent 110 the lower end thereof and in advance of said second named arm, a shank rotatably supported by the body, transversely spaced outstanding fingers carried by the shank, a cross member connecting said fingers intermediate their ends, an outstanding pin carried by the shank, said body being provided with a slot through which the pin is directed, yieldable means contacting with the opposite sides of the pin to normally maintain the fingers of the shank in substantially 115 a horizontal position, and an outstanding finger carried by the body adjacent the pin to determine the normal position of the fingers of the shank.

13. A mail handling apparatus comprising, in combination, a supporting crane provided with engaging means spaced longitudinally thereof, and a mail bag provided with engaging means carried by a side of 120 130

the bag and spaced longitudinally thereof for coaction with the spaced means of the crane.

14. A mail handling apparatus comprising, in combination, a supporting crane provided with engaging means spaced longitudinally thereof, and a mail bag provided with engaging means carried by a side of the bag and spaced longitudinally thereof for coaction with the spaced means of the crane, the spaced engaging means carried by the crane being yieldable.

15. A mail handling device comprising, in combination, a supporting crane provided with engaging means spaced longitudinally thereof, a mail bag, rings loosely engaged with the side of the bag at points spaced

longitudinally thereof and with which coact the spaced engaging means of the crane, and a flexible member connecting the rings.

20

16. A mail handling apparatus comprising, in combination, a supporting crane provided with engaging means spaced longitudinally thereof, a mail bag, hook members carried by a side of the bag at points spaced longitudinally thereof, said hook members facing inwardly, rings engageable with said hook members, and a flexible member connecting the rings, the engaging means of the crane coacting with said rings.

25

In testimony whereof I hereunto affix my signature.

30

JOHN A. STARR.
